ATTYS.

UNITED STATES PATENT OFFICE.

FRANK R. McCLUSKY, OF CANFIELD, OHIO.

MANIFOLDING SHEET.

1,423,808.

Specification of Letters Patent. Patented July 25, 1922.

Application filed May 4, 1920. Serial No. 378,855.

To all whom it may concern:

Be it known that I, FRANK R. McCLUSKY, a citizen of the United States, residing at Canfield, in the county of Mahoning and 5 State of Ohio, have invented a new and useful Manifolding Sheet, of which the following is a specification.

The invention relates to an improvement in blanks and more particularly to a blank 10 adapted for use in freight offices, and comprises a combination of bill of lading, shipping order, way bill, postal notice and copies of way bill together with receipts from the consignee and from the railroad.

15 The objects of the invention are the provision of a blank for use in railway freight offices, said blank including bill of lading, shipping order, freight way bill, postal notice, cashier's copy, consignee's receipt, 20 warehouse foreman's copy and auditor's copy of the way bill, all of these blanks being connected together in a single sheet and arranged to be folded in order that complete carbon copies may be imprinted upon 25 all of the different blanks with one writing, the several blanks being perforated at their edges in order that they may be detached after they are filled out.

With these objects in view the invention 30 consists in the novel construction and arrangement of parts, hereinafter described, illustrated in the accompanying drawings, and particularly pointed out in the appended claims, it being understood that 35 various changes in the form, proportions, size and minor details of construction may be made within the scope of the appended claims, without departing from the spirit or sacrificing any of the advantages of the 40 invention.

The invention thus set forth in general terms is illustrated in the accompanying drawings forming part hereof, in which—

Figure 1 is a plan view of the blank showing 45 the obverse sides of the bill of lading, original way bill, cashier's copy, warehouse foreman's copy and one of the auditor's copies of the way bill and the reverse sides of shipping order and office copy of 50 way bill, postal notice, consignee's receipt and one of the auditor's copies of the way bill.

Fig. 2 is a similar view showing the reverse sides of the bill of lading, original 55 way bill, cashier's copy, and one of the auditor's copies of the way bill and the obverse sides of the shipping order and office

copy of way bill, postal notice, consignee's receipt and one of the auditor's copies of the way bill.

Fig. 3 is an end view of the blank folded preparatory to writing.

Fig. 4 is a face view of the bill of lading.

Fig. 5 is a face view of the shipping order and office copy of the way bill.

Fig. 6 is a similar view of the original way bill.

Fig. 7 is a face view of the lower portion of the cashier's receipt or warehouse foreman's receipt; and

Fig. 8 is a fragmentary face view of a portion of the lower part of the consignee's receipt.

A practical embodiment of the invention is disclosed in the accompanying drawings, 75 forming a part of this specification in which similar numerals of reference indicate corresponding parts throughout the several views.

The invention comprises broadly the combination of blank forms for the original bill 80 of lading, the shipping order and office copy of way bill, the original way bill, the postal notice with copy of way bill on the obverse side, the cashier's copy of delivery receipt, the consignee's receipt from railroad, the 85 warehouse foreman's copy of delivery receipt and one or more copies of auditor's copy of way bill, all of these blanks being formed in a single continuous strip with perforations at the edges of the adjoining 90 blanks, each alternate blank being reversed upon the strip, certain of said blanks being provided with carbonized backs, carbon sheets being adapted to be used between certain other of the blanks, the entire strip being arranged to be folded in a zig-zag manner as shown in Fig. 3, bringing the carboned back of each blank in contact with the obverse side of the next adjacent blank.

As shown in Figs. 1 and 2 of the drawings, the device comprises a continuous strip composed of a plurality of blanks comprising the bill of lading indicated generally by the numeral 1, having upon its obverse side the blank form of a straight bill of lading such as will be later described, the reverse side thereof having printed thereon as shown at 2, the standard terms and conditions of straight bill of lading such as has been adopted generally by carriers.

Separated from the bill of lading by means of a vertical perforated line is a shipping order and office copy of way bill, indicated generally by the numeral 3, the face

thereof being upon the same side of the strip as the back of the bill of lading. The back of the blank 3 preferably has printed thereon, as shown at 2, conditions and terms the 5 same as shown on the back of the bill of lading.

Separated from the blank 3 by means of a vertical perforated line is the original way bill, indicated generally by the numeral 4, 10 the front face thereof being upon the same side of the slip as the bill of lading. The rear face of the blank 4 is carbonized to the point 6, near its lower end.

The postal notice, indicated generally by 15 the numeral 7, is located upon the same side of the strip as the original way bill and has on its opposite face a copy of the way bill, indicated generally by the numeral 8.

The cashier's copy of the way bill and 20 railroad company's delivery receipt to the consignee is separated from the postal notice by means of a vertical perforated line and located upon the same side of the strip as the bill of lading, original way bill and postal 25 notice, being indicated generally by the numeral 9. The rear face of the cashier's copy is carbonized as shown at 10, down to the line 6.

The consignee's receipt from the railroad 30 company for freight charges paid at destination, also contains a copy of the way bill and is located upon the opposite side of the sheet from the cashier's receipt and separated therefrom by means of a vertical perforated line, this blank being indicated generally by the numeral 11 and carbonized upon its rear face down to the line 6, as shown at 12.

The warehouse foreman's copy which is a 40 duplicate of the cashier's copy adjoins the consignee's receipt and is located upon the opposite side of the receipt from the consignee, the receipt being indicated generally by the numeral 13, the rear face thereof being carbonized as at 14, down to the line 6, a vertical perforated line separating said blank from the consignee's receipt.

In the drawing two copies of the auditor's copy of the way bill are indicated by the numerals 15 and 16, respectively, the copy 15 being located upon the reverse side of the sheet from the warehouse foreman's copy, while the copy 16 is located upon the same side of the sheet as the warehouse foreman's 55 copy and separated from the copy 15 by means of a vertical perforated line. The copy 15 is carbonized upon its back, as shown at 16, down to the line 6, and the copy 16 is provided with a blank rear face, as indicated at 18.

Attention is now directed to Fig. 4 of the drawings, which shows the front face of the bill of lading, indicated generally by the numeral 1. This blank is provided near its 65 lower end with an original line 6, which ex-

tends entirely across the entire sheet or strip as will be later described. The space above the line 6 is divided by a vertical line 19, into two substantially equal areas, the area on the right thereof having at its upper portion, at the point indicated by the numeral 20 on the drawing the following legend:

"Uniform bill of lading—Standard terms and conditions of straight bill of lading adopted by carriers in official classification 75 territory," beneath which the name of the railroad company and the title:

"Straight bill of lading—Original—Not negotiable" is located.

Beneath this title at the point indicated at 80 21, the following legend is located upon the blank:

"Received, subject to the classifications and tariffs in effect on the date of issue of this original bill of lading," beneath which are 85 blanks for date, waybill, number, station and State, beneath which in the space indicated by the numeral 22, the following printed matter is provided:

"From _____ to _____ the property described herein in apparent good order, except as noted (contents and conditions of contents of packages unknown), marked, consigned and destined as indicated herein, which said company agrees 95 to carry to its usual place of delivery at said destination, if on its road, otherwise to deliver to another carrier on the route to said destination. It is mutually agreed as to each carrier of all or any of said property over 100 all or any portion of said route to destination, and as to each party at any time interested in all or any of said property, that every service to be performed herein shall be subject to all the conditions, whether 105 printed or written, herein contained (including conditions on back hereof) and which are agreed to by the shipper and accepted for himself and his assigns."

Beneath this printed matter and extended 110 entirely across the bill of lading at the point marked 23, is a plurality of vertical spaces extending downwardly to the line 6 and containing the following headings:

"Lading—Weight—How obtained—Rate 115 and tariff No.—Freight—Advances and pre-paid."

In the upper left hand corner of the bill of lading in the space marked 24 the following instructions are preferably printed:

"This form must be written with typewriter—billing machine or indelible pencil.—If written with typewriter use hard roll and strong stroke to insure the best copies.—(If indelible pencil is used place papers on 125 metal sheet and write plainly and bear on heavy.) Use loose leaf carbon sheets in the 1st, 2nd and 4th fold. Top fold full length carbon, 2nd and 4th fold carbon only to line marked."

Beneath this printed matter are spaces for the car initials and car number, route, station and State of destination, consignee and address and instructions regarding icing, 5 ventilation, milling, weighing, etc.

In the lower left hand portion of the bill of lading below the line 6 are provided lines for the shipper and his agent, while in the lower right hand portion of the blank are 10 provided spaces for the freight agent and his representative to sign.

In Fig. 5 is shown the face side of the shipping order and original way bill. The shipping order, indicated generally by the 15 numeral 25, is located to the right of the vertical line 19 and the original way bill indicated generally by the numeral 26 is located at the left of said line. The shipping order is a duplicate of the right hand 20 portion of the bill of lading with the exception that the title "Shipping order" is placed in the upper right hand side thereof, followed by short instructions to the agent. At the upper left hand side of this blank the name of 25 the railroad company, and the title, freight way bill are provided beneath which are spaces for instructions for stopping the car, weight of car and conditions and car movement record. Beneath this, the remainder 30 of the way bill corresponds with the upper left hand portion of the bill of lading and the portion 23 corresponds with the similar portion of the bill of lading. Beneath the line 6 are provided spaces for the shipper or his 35 agent to sign corresponding with the similar spaces upon the bill of lading.

In Fig. 6 is illustrated a face view of the original way bill. The upper portion of this blank upon the left side of the vertical line 40 19 corresponds with the office copy of the way bill shown at 26 in Fig. 5.

In the upper right hand corner of this blank is the following:

"Yard stamp must not be shown on face 45 of this way bill," beneath which is provided spaces for showing transfer, car number and the place. The portion of the way bill beneath this point down to the line 27 corresponds with the similar portion of the shipping order. From this point down to the 50 area 23 are provided spaces for the length of the car, marked "Capacity of the car" stenciled weight of car, reference numbers, together with a table of symbols showing how 55 weight were obtained and spaces for showing data of weighing.

The area 23 corresponds with the similar areas on the bill of lading and shipping order. Beneath the line 6 is provided a plurality of spaces for affixing junction stamps. The back of this blank is carbonized down 60 to the line 6, the postal notice has upon its back a duplicate of the way bill indicated generally by the numeral 8. Beneath the 65 lines 6 thereon at 29, the following instruc-

tions are printed, "Detach at perforated line, fold, address and complete other side."

The front side of the postal notice is divided into four equal areas by means of the vertical and horizontal lines 30 and 31. The 70 two upper areas are blank. The lower right hand area 33 is provided with lines for name and address of consignee and place for a postage stamp and the other area 7 contains the postal notice proper.

The cashier's copy indicated generally by the numeral 9 is a duplicate of the way bill above the line 6 and beneath said line is provided with blank for receipt of railroad company's delivery to consignee, spaces being 80 provided for the station stamp and date delivered and signatures of the clerk making delivery and consignee. Spaces are also provided upon the lower portion of this blank for filling in the freight bill No. or 85 pro. No., date received at destination, storage charges, etc., with space for the agent's signature and certificate of the party mailing the postal notice, giving the time, date, etc.

The consignee's receipt, indicated generally by the numeral 11 contains a duplicate of the way bill above the line 6 and beneath the line 6 the portion upon the left side of the line 19 is a duplicate of the corresponding 95 portion upon the cashier's copy while the area upon the right of the line 19 as indicated at 35 contains a blank form of receipt from the railroad company to the consignee for payment of freight charges with spaces for 100 the station stamp and signature of the agent.

The warehouse foreman's copy, indicated generally by the numeral 13 is an exact duplicate of the cashier's copy. The auditor's copy of which there may be either one or 105 two as indicated at 15 and 16 upon the drawings is an exact duplicate of the original way bill, although the area beneath the line 6 is preferably left blank as indicated at 36.

In use the sheet is folded in a zig-zag manner as shown in Fig. 3, the face side of the bill of lading being upon the top, a carbon sheet 37 of the same size as the bill of lading is placed between the bill of lading and the shipping order and a carbon sheet 38 extending down to the line 6 is placed between the shipping order 3 and the original way bill 4. A carbon sheet 39 of the same size as the sheet 38 is placed between the postal notice 7 and the cashier's copy 9.

The bill of lading is then filled out either with typewriter, billing machine or indelible pencil, thus making a duplicate carbon copy of the matter written upon the bill of lading upon each of the other blanks. The 125 shipper or his agent then signs the bill of lading in the space provided therefor, after which the bill of lading is detached at the perforated line from the shipping order and signed by the freight agent in the space 120 125 130

provided therefor and given to the shipper. The signature of the shipper will thus be transferred upon the shipping order, while the signature of the freight agent does not 5 appear thereon.

In the event that the shipper prepays the charges the freight agent will sign the receipt provided therefor at 40, upon the bill of lading and shipping order, signing both 10 of these receipts after detaching. Should the shipper desire a memorandum bill of lading, a loose sheet having substantially a duplicate of the straight bill of lading may be placed between the bill of lading 15 and the shipping order with a carbon sheet between and this memorandum of the bill of lading is also given to the shipper.

The shipping order and office copy of way bill 3 is then detached and kept at the office. 20 The auditor's copies are also detached and forwarded to the auditor of freight accounts at the general office.

The original way bill, postal notice, cashier's copy, consignee's receipt and warehouse foreman's copy, are left in the folded condition and again folded lengthwise upon the line 19, a paper fastener being placed over the edges of said papers at the point indicated by the numeral 41 and these 25 papers are then given to the conductor of the freight train carrying the shipment of goods to which they apply and are turned over by the conductor to the freight agent at the destination.

35 The freight agent at the destination detaches the postal notice and fills out the consignee's name and address and the blank 7 and folds the same upon the lines 30 and 31, bringing the portion 33 upon the outside after which a paper fastener is placed 40 over the edges thereof and a stamp placed thereon and the postal notice is mailed to the consignee.

The cashier's copy and the warehouse 45 foreman's copy are filled out by the freight agent at the destination and signed by him and the consignee upon the delivery of the goods to the consignee and are filed in the cashier's office and warehouse at the destination.

50 The consignee's receipt is also filled out and signed by the agent upon receipt of payment of the freight charges from the consignee and is delivered to the consignee.

55 It will be evident from the above description that the blank provided will not only save time and labor as all of the different forms are filled out with one writing, but each copy will be an absolute copy of the 60 original bill of lading and thus provides an accurate check upon the shipper and shipping agent and prevents claims for damages caused by an error in filling out the different blanks.

65 A bill of lading cannot be given without

the way bill being made to carry the shipment to destination, receipt already prepared for delivery to consignee, thus enabling the carrier to make immediate delivery at the point of destination.

70 It will, of course, be understood that in the event perishable freight is being shipped the way bill could have shown thereon a red stripe such as is at present being used upon way bills to indicate perishable freight.

75 If desired a loose leaf carbon sheet may be used between the way bill and postal notice instead of carbonizing the back of the way bill.

80 Each set of these papers will be lettered or initialed or numbered in the way bill number space provided thereon so that the same initial and number will appear throughout the entire set and each set of papers will have only one number and initial, each shipment having a different number.

85 This invention saves labor, time, errors, claims, unpleasant correspondence, money and gives better service, better satisfied patrons, the good will of the public and more business for the carrier using this invention.

90 Instead of the shipping instructions being written on bill of lading when shipment is offered for forwarding, and this information rewritten on way bill by forwarding office, and the same information again rewritten from way bill to expense bill or (consignee's receipt) at destination these 95 papers are all written at one writing (when the bill of lading is written) making only one-third the actual writing now required to handle any shipment, in addition to saving fifty per cent of the work required preparing postal notice at destination, and also in addition to this all large corporations have their own tariffs departments which

100 are headed by practical railroad traffic men who have the same tariffs and rates as the 110 carriers and these corporations prepare their own bills of lading, which is estimated to be eighty per cent of the total shipments handled by all carriers. These men are as

115 capable of properly preparing these papers as the carriers' employees and are glad to have the opportunity to carefully make proper billing covering their own shipments. The result is as follows:—For every one thousand shipments now made the carriers' 120 employees must make two hundred bills of lading, one thousand way bills and one thousand expense bills (or consignee's receipts), making a total of two thousand, two hundred bills made by carriers' employees 125 —other corporation's shipping departments preparing the other eight hundred bills of lading.

130 By using this invention the carriers' employees make only two hundred bills in

stead of two thousand, two hundred bills, beside saving fifty per cent of the work at destination preparing postal notice to consignee—other corporation's shipping department making the other eight hundred bills of lading, same as at present.

There are no way bills to make for way bill is already prepared when bill of lading is made. There are no delivery receipts or expense bills to make at destination for these are also made when bill of lading is made.

All papers are prepared at one writing when bill of lading is made and no time required to make way bill at forwarding office or to make delivery receipts at destination giving more prompt service and immediate delivery to consignee on arrival at destination.—No time required of consignee waiting for delivery receipts to be made up at destination which makes better pleased patrons.—No time required holding merchandise cars at forwarding office waiting for way bills to be made.

The way bill number appears on each bill of lading and in tracing shipper quotes number to forwarding agent which he can immediately locate in his complete file instead of wasting time, first finding shipping order and then finding way bill to cover.

By using this invention a bill of lading cannot be issued without all other papers complete, including way bill to carry shipment to destination and delivery receipt already prepared for delivery to consignee.

Way bill cannot be omitted on any shipment for which bill of lading is issued and way bill and delivery receipt from consignee will read exactly as carrier received for to shipper on bill of lading. No more errors made in omission or mistakes in copying from bill of lading to way bill or in copying from way bill to delivery receipt at destination. No wrong delivery in way billing. No wrong destination on way bill. No wrong consignee and address on way bill. No wrong routing on way bill, and other errors too numerous to mention will be overcome as way bill will read exactly as received for to shipper on bill of lading.

This invention will save thousands of claims, each year caused by errors in wrong way billing, wrong delivery, wrong routing, wrong consignee, wrong destination. Articles omitted from way bill and lost in transit, articles received for to shipper on bill of lading and no way bill to cover and lost in transit without billing and many other errors in way billing other than as received for to shipper on bill of lading.

The invention saves unpleasant correspondence, made necessary on account of said errors and claims and makes better satisfied employees and better satisfied patrons.

This invention will save the carriers many thousands of dollars each month now paid

to clerks for making way bills and delivery receipts and for clerks now necessary to handle the claims and correspondence caused by errors and many thousands of dollars each year for claims paid account of said errors.

This invention gives more prompt service in forwarding, more prompt service in delivery at destination and full and complete way bill reference for every shipment forwarded which is of great advantage to shipper in tracing.

This invention gives more prompt service afforded in both forwarding and delivering and full and complete way bill reference furnished on every shipment and the assurance every shipment is going to travel exactly as per bill of lading and that there will be no unpleasantness or claims account of same not being forwarded as desired,—the shipper and the public will naturally patronize and prefer the carrier using this invention which means more business for the carrier using this invention.

While it is recommended the plan herein described be used in numbering way bills, if for any reason any carrier wishes to number way bills each month as is the present system, the way bill series and number may be placed on the bill of lading in the space provided therefor by the agent at forwarding station when shipment is accepted for transportation and bill of lading signed.

The blank form for the bill of lading may be worded to cover an order bill of lading, if desired, instead of a straight bill of lading, by changing the word "Straight" to "Order" in the two places at the heading in the bill of lading and in one place at the heading of the shipping order and adding the words "Order of" in the consignee's space on all forms and by adding the word "Notify" at the bottom of the consignee's space, and by providing a space for endorsements on the back of the bill of lading above the printed conditions thereon.

The following clause should also be added across the face of the bill of lading and shipping order at any convenient point, preferably in the space 22: "The surrender of this original order, bill of lading properly endorsed shall be required before the delivery of the property. Inspection of property covered by this bill of lading will not be permitted unless provided by law or unless permission is endorsed on this original bill of lading or given in writing by the shipper."

I claim:

1. A manifolding sheet divided by lines of weakening into a plurality of substantially equal sections, a line parallel with the bottom of said sheet and located through all of said sections, said sheet being provided with printed forms above said line on alter-

nate sections on the obverse side, and on the remaining sections on the reverse side of the sheet, the first and second sections having similar printed forms below said line and 5 arranged to receive a carbon sheet therebetween, the remaining sections having different printed forms below said line and arranged to be filled in at different later intervals, one of the intermediate sections hav- 10 ing a printed form upon each side of the sheet, the remainder of said sections being provided with carbon surfaces upon their backs extending down to said line, whereby at a single writing the first and second sections are filled out above and below said line and the remaining sections are filled out above the line only.

2. A manifolding sheet divided by lines of weakening into a plurality of substantially equal sections, a line parallel to the bottom of said sheet and located through all of said sections, said sheet being provided with printed forms above said line on alternate sections, on the obverse side, and on the 25 remaining sections on the reverse side of the sheet, the first and second sections having similar printed forms below said line and arranged to receive a carbon sheet therebetween, one of the intermediate sections 30 having a printed section upon both sides of the sheet, the remainder of said sections being provided with carbon surfaces upon their backs extending down to said line whereby at a single writing the first and 35 second sections are filled out above and below said line and the remaining sections are filled out above the line.

3. A manifolding sheet divided by lines

of weakening into a plurality of substantially equal sections, a line parallel with the 40 bottom of said sheet and located through all of said sections, said sheet being provided with printed forms above the line on the first, third, fifth and seventh sections on the obverse side of the sheet and on the second, 45 fourth, sixth and eighth sections on the reverse side of the sheet, the first and second sections having similar printed forms below said line, the entire first section being provided with transfer material on the reverse 50 side of the sheet and the backs of the remaining sections being provided with transfer material extending down to said line.

4. A manifolding sheet bearing suitable imprints divided by lines of weakening into 55 bill of lading, shipping order, freight way bill, postal notice, cashier's copy, consignee's receipt, warehouse copy, an auditor's copy of way bill, a line parallel with the bottom of said sheet and located through 60 all of said forms, the bill of lading and shipping order having similar printed forms below said line, the remaining forms having different printed forms below said line, the bill of lading being provided with trans- 65 verse material covering the entire reverse side thereof, the remaining sections having transverse material extending down to said line whereby at a single writing the bill of lading and shipping order are filled out 70 above and below said line and the remaining forms are filled out above the line only.

In testimony that I claim the above, I have hereunto subscribed my name.

FRANK R. McCLUSKY.
